United States Patent Office.

HAYWARD A. HARVEY, OF ORANGE, NEW JERSEY.

Letters Patent No. 72,633, dated December 24, 1867.

IMPROVEMENT IN WOOD-SCREWS.

The Schedule referred to in these Letters Patent and making part of the same.

TO ALL WHOM IT MAY CONCERN:

Be it known that I, HAYWARD A. HARVEY, of Orange, in the county of Essex, and State of New Jersey, have invented a new and useful Improvement in Wood-Screws; and I do hereby declare that the following is a full, clear, and exact description thereof.

The nature of my invention consists in so forming the core of a screw as to cause the upper portion of it to present the appearance of a series of truncated cones between the threads, one above the other, with their bases toward the point, which I accomplish by so shaping and setting the chasing-tool as to cut the threads deeper on the under side than on the upper, as will be readily understood by those accustomed to the manufacture of screws. The core or body of the screw is thus made to operate upon the wood, into which it is inserted in the manner of a wedge, with its point toward the surface, thus imparting to the screw an increased power of resistance to withdrawal. Moreover, in displacing the wood to make room for itself, a screw of this form crowds the wood backward or toward the surface, thus compacting it in that direction, which is obviously advantageous in increasing its holding qualities.

The drawings, which accompany and form a part of this specification, embrace an enlarged external view, and a longitudinal section of my invention, similar letters of reference being used to indicate the same parts of both figures.

a represents the head, *b* the shank, *c* the thread, *d* the core, and *e* the point.

Figure 2 represents a section of the screw in use, *f* and *g* being two pieces of wood joined together by it; and in speaking of the surface of the wood I refer to *h*, in which the head is embedded.

What I claim as my invention, and desire to secure by Letters Patent of the United States, is—

A screw, constructed in the ordinary manner, with the exception that the thread is cut deeper on the under side than on the upper, substantially as and for the purpose set forth.

H. A. HARVEY.
